Bronislaw Wandel, Boston, Mass.

Application July 3, 1944, Serial No. 114,295

Term of patent 7 years

(Cl. D17—6)

To all whom it may concern:

Be it known that I, Bronislaw Wandel, a citizen of the United States, residing at Boston, in the county of Suffolk and State of Massachusetts, have invented a new, original, and ornamental Design for Clamp for Bedclothes, of which the following is a specification, reference being had to the accompanying drawing, forming part thereof.

I claim:

The ornamental design for a clamp for bedclothes, as shown.

BRONISLAW WANDEL.
